Inventor:

Thomas Raser

United States Patent Office.

THOMAS RASER, OF GENESEO, ILLINOIS.

Letters Patent No. 69,366, dated October 1, 1867.

IMPROVED BED-BOTTOM.

The Schedule referred to in these Letters Patent and making part of the same.

TO ALL WHOM IT MAY CONCERN:

Be it known that I, THOMAS RASER, of Genesee, in the county of Henry, and State of Illinois, have invented a new and useful Improvement in Spring-Beds; and I do hereby declare that the following is a full and exact description thereof, reference being had to the accompanying drawings, and to the letters of reference marked thereon.

The nature of the invention consists in the construction of a spring-bed which will be durable, cheap in its manner of construction, easy to adjust, and at the same time secure to the occupant health, ease, and comfort.

To enable others skilled in the art to make and use my invention, I will proceed to describe its construction and operation.

Figure 1 in the accompanying drawings is a perspective view of all parts attached.

Figure 2 is a section through the boxing or casting C and that part of the pole or bolster B at the points of bearing on the rubber bands D.

I make my bedstead or frames in any of the known forms, having sufficient width or depth of rail to apply or attach my improvement, as shown at A A in fig. 1. I make the boxing C out of cast iron, with a round bar on a line with the slugs or projections through which the upper screws pass, this bar being one of the points of bearing for the rubber bands D D, as shown in figs. 1 and 2. I make the bottom of the boxings or castings beveling, for the purpose of strength, as also to accommodate the inclining position of the rubber bands, as shown in fig. 2. On the inside of both of the rails A A I insert or let in four or more of the castings C, so that they are flush with the outer surface of the rails, as shown at A in fig. 2. I fasten my castings to the rails by means of screws, as shown in fig. 2. I make the pole B out of any suitable timber, rounding the points of bearing for the reception of the bands D D, as shown in figs. 1 and 2. I form the rings or connection in the rubber bands by first passing the end around the rounded bar in the casting, and, lapping the ends thereof, fasten them together by means of rivets or eyelets. The pole can then be passed through and taken out at will. In order to hold the poles and slats E to their places, and prevent the poles from rubbing the side rails, &c., I dovetail the poles and the two end slats together, as shown at one point in fig. 1.

What I claim as my invention, and desire to secure by Letters Patent, is—

The boxing or castings C and poles B B, in combination with the rubber bands and slats D and E, as described.

THOMAS RASER.
